UNITED STATES PATENT OFFICE.

JOHN ROBERT KELLEY, OF COVINGTON, KENTUCKY.

CONTROL SWITCH.

Original application filed June 2, 1921, Serial No. 474,464. Divided and this application filed January 25, 1924. Serial No. 688,371.

This is a divisional application of my application Serial No. 474,464, filed June 2, 1921.

An object of my invention is to provide a control switch which may be shunted across the power lines and which will preclude initial overloading of a motor.

Another object is to provide a switch of this type that may be used to automatically lock a circuit closing mechanism against closing unless the mechanisms are in their proper relation before starting the motor.

Another object is to provide a device for the purposes stated that is simple in operation and construction.

These and other objects are attained by the means described herein and disclosed in the accompanying drawings, in which:

Fig. 1 is a fragmental side elevation of a frame having mounted upon it a control switch and co-operating mechanism of my invention.

Fig. 2 is an enlarged sectional view taken on line 2—2 of Fig. 1.

Fig. 3 is a diagrammatical view of the wiring of a control switch and an operating switch and motor showing a modified form of the control switch of my invention.

My invention comprises a control switch comprising a housing 5 mounted upon a frame 6 and containing a sleeve 7 of some non-magnetic material, such as brass, about which extends an electric winding coil 8 which is adapted with the magnetic core 9 disposed within the sleeve 7 to form an electromagnet. The core 9 has a central bore 10 therein through which extends a reciprocating rod 11 having mounted upon it an armature 12 adapted to be attracted by the

core 9 when the electromagnet is energized.

A non-magnetic collar 13 is mounted upon the rod 11 adjacent one end thereof, which end extends through the frame 6 and has mounted upon it a suitable handle or knob

14, whereby the rod 11 may be longitudinally reciprocated in the sleeve. A key 15 may be employed to preclude rotatory motion of the rod 11. A block 16 upon which the housing is mounted, spaces the forward end

of the housing from the rear of the frame 6. A metallic ring 160 of magnetically responsive material spaces the rear end of the sleeve from the rear end of the housing. The block 17 mounted on the housing and

through which the rod 11 extends, has 55 mounted upon it a metallic band 18 having a conical face. The metallic band is electrically connected with an operating switch 19 (see Fig. 1) of the type disclosed in my co-pending application, Serial Number 60 474,464. The rear end of the rod 11, or in other words the end spaced from the knob 14, has mounted upon it a block 20 of insulating material upon which is mounted 65 spring contact arms 21 adapted to make an electrical connection with the conical face of the metallic band 18 and when the arms are moved into contact with said band, they are tensioned so that when the force that holds the arms in contact with the ring is 70 withdrawn, the tendency of the spring arms is to assume their normally unstrained positions and causes the rod 11 to be moved longitudinally in such direction that the arms 21 are disengaged from the band 18. 75 The spring contact arms are electrically connected by means of a flexible conductor 23 with a conductor post 22 mounted upon the block 16 adjacent the housing 5. The core 9 and the armature 12 bear such relation 80 that when the electromagnet is energized when the handle 14 is shifted, at which time the contact arms 21 will move into engagement with the metallic band 18 and the armature 12 will assume a position in immediate proximity to the core and will be retained in such position by the magnetic attraction of the core against the yielding resistance of the spring arms 21. The winding 8 of the electromagnet is electrically 85 connected with the band 18 and the return wire 24 of the line circuit.

A source of electrical supply 26, represented in this case as a battery, has one of its poles connected with the said line wire 95 25 and its other pole connected to the return line wire 24. The line wire 25 is electrically connected with the conductor post 22. The current passing through the line wire 25 and through the control switch passes to an operating switch 19 (see Fig. 1) by way of the wire 27. A locking arm 28 is mounted intermediate its ends upon a pivot 29 on the frame 6. One end of the arm 28 is adapted to engage a collar 30 which is pivotally mounted on a shaft 31 which forms a part 100 of the operating switch 19. The other end is adapted to be moved intermediate the

collar 13 mounted on rod 11 and the frame 6 and to thereby preclude longitudinal movement of the rod 11 toward the frame 6 wherefore it is impossible when locking arm 28 is in such intermediate position to make electrical contact between the spring contact arms 21 and the metallic band 18. A spring 32 normally retains the locking arm 28 in engagement with the collar 30. The collar 30 has a face 33 formed thereon disposed in such position that when the conductor bars 34 of the operating switch 19 engage contacts 35, the face 33 on the collar 30 will be exposed to and contacted by the rod 28. The control switch as described is adapted to control an electrical connection between the wires 24 and 25 or is in other words a one pole switch. In Fig. 3 is shown a double pole control switch which is a modification of the control switch shown in Fig. 2. In this construction the metallic band is formed in two pieces 36 and 37 which are insulated from one another and each of which is adapted to make an electrical connection with one of the spring arms 21, of which one is connected to the said wiring 25 and the other is connected to the return wire 24. In this construction the key 15 precludes relative rotatory motion of the rod 11 and the metallic band sections 36 and 37, wherefore the direction of the flow of current will not be modified by the control switch. It is also necessary in this form to provide two conductor rods 22 and two flexible metallic conductors 23. A suitable line switch 38 is interposed between the source of electrical supply 26 and the control switch. The operation of the device is as follows.

Assuming that the parts are in the relation as shown in Fig. 1, the spring contact arms 21 are in the position shown in Figs. 2 and 3. The handle 14 is then pulled away from the frame 6 to a position shown in dotted lines in Fig. 2, therefore causing the spring contact arms 21 to engage the metallic band 18 and energizing the electro-magnet contained within the housing 5, wherefore the armature 12 will be retained in such position by the magnetized core 9, that the spring arms 21 will remain in contact with the metallic band. The operating switch 19 is then actuated so that current is directed through wires 40 and 41 containing resistances 42 and through the resistances to the motor.

After the motor armature has begun to revolve, the operator releases the handle of the switch 19, whereupon the contact arms 34 are caused to engage contacts 35, at which time the motor received a full load current.

Assuming now that the line switch 38 is opened, wherefore the electromagnet in the control switch is de-energized, and the action of the spring arms 21 causes the rod 11

to be moved longitudinally to such an extent 65 that the contact between the spring arms 21 and the metallic band 18 is broken. This movement of the rod 11 serves to move the collar 13 away from the frame 6, whereupon the end of the arm 28, which was being held in engagement with the collar 13 by means of the spring 32, is separated from the collar 13, wherefore the spring 32 moves the arm 28 about its pivotal mounting 29 and causes the arm 28 to engage upon the face 33 of the collar 31. When the arm 28 is in this position, the end thereof adjacent the control switch assumes a position intermediate the collar 13 and the frame 6, wherefore it is impossible to move the rod 11 to such an extent as to again bring the spring contact arms 21 into engagement with the metallic band 18.

From the foregoing it will be readily apparent that the only way in which it will be possible to again energize the motor will be by revolubly actuating the means upon the operating switch 19 so that the collar 31 thereof will cause the arm 28 to move from the position it now assumes intermediate the collar 13 in the frame 6. When the operating switch 19 has been thus properly actuated for the purposes stated, the parts are again put in position as shown in Fig. 1 and in readiness to again start upon the motor by directing the current first through the control switch and the wires 40 and 41 and resistance 42, until the armature of the motor has begun to revolve, at which time the operating switch 19 may be actuated to 100 throw the full load current onto the motor.

What I claim is:

1. In a control switch the combination of a housing, a sleeve within the housing, an electrical winding about the sleeve, a core 105 within the sleeve adapted with the winding to form an electro-magnet and having a bore therethrough, a rod mounted reciprocally in the bore, a handle mounted on one end of the rod, spring contact arms mounted upon the other end of the rod, a tapered metallic plate electrically connected with one end of the winding mounted about the sleeve, adapted to be engaged by the spring contact arms, an armature mounted upon the rod adapted 110 to contact the electro-magnet and to be retained in contact with the electro-magnet to thereby retain the spring contact arms in engagement with the metallic band, a collar mounted on the rod, and means adapted 115 to be conditioned to preclude movement of the collar and to thereby control engagement of the contacts and the metallic plate.

2. In a control switch the combination with a frame having an aperture therethru, a block mounted in spaced relation to the frame and having an aperture registering with the aperture in the frame, a housing 125

mounted on the block, a magnetic core having an axial bore mounted within the housing, a nonmagnetic sleeve surrounding the core, an electric winding disposed about the sleeve within the housing, a rod extending reciprocally thru the registering perforations in the frame, the block and the axial bore in the core, a handle on one end of the rod adjacent the frame, a nonmagnetic collar 10 on the rod adapted to reciprocate thru the aperture in the block, an armature mounted on the rod for reciprocation within the sleeve, a metallic band mounted upon the housing and electrically insulated therefrom, an electrical connection between the band and one end of the electric winding, spring contact arms mounted on the end of the rod and adapted to be carried into contact with the metallic band and means associated with the frame for limiting the re-

ciprocation of the rod whereby the contact arms are precluded from contacting the metallic band.

3. In a control switch mechanism the combination with an electromagnet, a metallic band electrically connected with the electromagnet, an armature reciprocable through the electromagnet, insulated contacts carried by the armature, for engagement on the metallic band when the armature is moved toward the electromagnet for energizing the magnet whereby the contacts are retained in engagement with the metallic band and mechanical means to preclude movement of the armature toward the electromagnet. 85

In testimony whereof, I have hereunto subscribed by name this 14th day of January, 1924.

JOHN ROBERT KELLEY.
